TRAINING AID FOR BASKETBALL PLAYERS
OR THE LIKERobert L. Kirchner, 544 Kling Drive,
Dayton, Ohio 45419

Filed Dec. 4, 1972, Ser. No. 312,204

Term of patent 14 years

Int. Cl. D19—07

U.S. Cl. D25—1 R

FIG. 1 is a perspective view of a training aid for basketball players or the like taken generally from the front of the device.

FIG. 2 is a perspective view taken generally from the rear of the device.

FIG. 3 is a side elevational view of the device illustrating its appearance when worn on the head of a user, which head is shown in broken lines for illustrative purposes.

FIG. 4 is a front elevational view of the device.

FIG. 5 is a plan view of the device.

I claim:

The ornamental design for a training aid for basketball players or the like, as shown and described.
